UNITED STATES PATENT OFFICE.

ISADORE JOSEPH LEVY, OF NEW YORK, N. Y.

DESIGN FOR A HAND-BAG.

40,461.

Specification for Design.

Patented Jan. 25, 1910.

Application filed December 1, 1909. Serial No. 530,884. Term of patent 3½ years.

To all whom it may concern:

Be it known that I, ISADORE JOSEPH LEVY, a citizen of the United States, and a resident of the city, county, and State of New York, have invented a new, original, and ornamental Design for Hand-Bags, of which the following is a specification, reference being had to the accompanying drawing, forming a part hereof.

The figure is a view in elevation of a hand bag showing my design.

The design is composed of two elements, namely, a base or wall part, substantially of the configuration shown and a plaited strip disposed vertically thereon.

I claim:

The ornamental design for a hand bag as shown and described.

ISADORE JOSEPH LEVY.
